UNITED STATES PATENT OFFICE.

PAUL MAUSER, OF OBERNDORF-ON-THE-NECKAR, GERMANY.

SAFETY MECHANISM FOR FIREARMS.

1,047,672.

Specification of Letters Patent. Patented Dec. 17, 1912.

Application filed July 27, 1910. Serial No. 574,079.

To all whom it may concern:

Be it known that I, PAUL MAUSER, doctor of engineering, royal privy commercial councillor, residing at Oberndorf-on-the-Neckar, in the Kingdom of Wurttemberg, Germany, have invented certain new and useful Improvements Relating to Safety Mechanism for Firearms, of which the following is a full, clear, and exact description.

10 The present invention relates to a firing pin arrangement comprising locking mechanism which, when the breech is being locked, holds the firing-pin behind the face of the breech bolt until the latter has arrived in

15 the closed position, so that the point of the firing pin cannot project beyond the face of the breech bolt and, consequently, cannot be released until the breech is positively locked.

There are numerous locking devices of 20 this description but they do not insure that the locking of the breech bolt has actually been effected before the firing pin is released, and this applies particularly to those weapons in which the breech bolt is locked 25 by special parts arranged independently of the breech-bolt, such as locking levers or the like.

The movements in modern recoil loaders are, as is well known, extremely rapid so 30 that even when the breech bolt is in its closed position it is not locked at the same moment, as is the case with the ordinary hand loaders. For this reason the known action between the breech bolt and lock for 35 the firing pin is not satisfactory. The necessity has therefore arisen for making the firing pin locking device dependent on the breech bolt locking mechanism so that the release of the firing pin does not only depend on the breech bolt being in its closed 40 position but also upon its being locked. With this end in view the present invention relates to a firing pin arrangement for fire arms, especially recoil loaders with fixed 45 barrels, in which the detent for locking the firing-pin, *i. e.*, for holding back the point of the firing pin or the like behind the breech bolt until the breech is locked, is positively operated by the breech bolt locking 50 mechanism so that the detent is only released and the point of the firing pin allowed to assume its position for firing after the breech bolt is locked. Thus the locking of the firing pin is dependent on the locking 55 of the breech bolt so that in no case can the

weapon be fired even by accident without the breech having been previously locked.

In the accompanying drawings the new firing pin arrangement is shown applied to a recoil loading rifle of "Mauser's system", 60 as set forth, for example, in U. S. Patent No. 971,061, September 27, 1910.

Figure 1 shows the parts in side elevation. Fig. 2 is a side elevation partly in section and with parts removed and Fig. 3 is a 65 horizontal section with the breech bolt closed but not locked. In Figs. 2 and 3, the detent is shown holding back the firing pin with its point in the non-firing position behind the front of the breech bolt. Figs. 70 4 and 5 are respectively a side elevation and horizontal section showing the position of the parts with the detent out of engagement and the point of the firing pin in front of the face of the breech bolt. Fig. 6 is a 75 cross section through the front end of the breech bolt. Fig. 7 is a plan and side view of the detent, and Fig. 8 is a side and front view of the forward end of the firing pin. Figs. 9 and 10 are top plan views (with the 80 cover plate removed) of a rear continuation of the portion of the gun shown in Figs. 3 and 5, showing the breech bolt locking device in open and closed position, respectively.

The weapon shown consists essentially of the stock or frame *g*, the lock casing *h* the front of which carries the barrel *l*, and the breech bolt *k* which makes its closing and opening movement in the said casing and 90 contains the firing pin *r*. The locking mechanism for the firing pin consists of a pivoted detent *e* which is arranged in the front part of the breech bolt, projects through a lateral cavity *k*¹ in the side of the latter and 95 is pivoted to the pin *c*¹ on a bar *c* placed from above into the breech-bolt and held in position by the extractor spring. In the center, above the end of the firing pin the detent has a rear nose *e*² which acts on a 100 corresponding inclined part *r*² on the collar *r*¹ of the firing pin *r*. At the side the detent has a wing like projection *e*¹ which rests against the inner wall of the casing *h* during the opening and closing of the breech bolt and, by the nose *e*² acting on the full 105 part of the collar on the firing pin, the detent holds the latter back against the pressure of its spring in its rearward position, as shown in Fig. 3. At the front end of the 110

path of the breech bolt a slot h^1 is provided in the casing into which the wing e^1 can fall as soon as the breech bolt is in its closed position. The important part is, as previously mentioned, the arrangement whereby the function of the detent e is made dependent on the locking of the breech bolt. For this purpose a sliding bar f is arranged at the side of the casing h , the front inwardly bent end of said bar passing through the slot h^1 in said casing h in front of the wing e^1 on the detent. This bar f is actuated by the cam plate a which is slidably mounted upon the firearm and effects the displacement of the locking levers b b , the pins b^1 b^1 of which engage the slots a^1 a^1 of the cam plate a . When the breech-bolt k is locked, the cam plate a is in its backward position and holds the levers b b inward with their faces against the rear end of the breech-bolt k (Figs. 5 and 10). When the breech-bolt k is unlocked, the cam plate a is in its forward position and the locking levers b b stand outward allowing the breech-bolt k thus unlocked to pass back between them (Figs. 4 and 9). The cam plate operates by inertia to actuate the locking levers b b to unlock the breech-bolt k upon recoil of the firearm and is automatically returned by a spring to its initial position to actuate the levers to lock the breech-bolt k . The sliding cam plate a is provided with an externally projecting finger-piece a^4 to enable it to be adjusted by hand. The bar f is connected to the sliding cam plate by the rear end f^2 engaging in a cavity a^2 in the finger piece a^4 , which is of such dimensions that a certain amount of play is allowed for movement in one direction, but which, when moved in the other direction, pulls the bar f with it. In the former case, in which the cam plate unlocks on being moved forward and locks on being moved backward, the cavity a^2 is so arranged that when the cam plate moves backward the front edge of the cavity a^2 meets the end f^2 in the last stage of the movement and pulls back the bar f with it, so that the detent e is moved from its locking position (Fig. 3) into its unlocking position (Fig. 5). The unlocking position is therefore only reached when the sliding cam plate is fully back, so that the firing pin is only then able to spring forward into its firing position with its point projecting beyond the end of the breech bolt. When, on the contrary, the sliding cam plate is moved forward, that is to say, when the breech is unlocked, the rear edge of the cavity a^2 pushes the bar f forward so that when the breech bolt goes back the detent e is swung back to the side of the casing into the locking position (Fig. 3) where it remains until the breech bolt having closed, the sliding cam plate, which acts on the locking levers b for locking the

breech bolt while going back turns the detent again in the opposite direction. Thus, whereas previously the detent e rested with its nose e^2 against the inclined part r^2 of the collar r^1 on the firing pin, the same now lies in the locking position on the full part, i. e. on the upper edge of the inclined part r^2 as shown in Fig. 3, thereby holding back the firing pin.

What I claim as my invention and desire to secure by Letters Patent is:

1. In an automatic firearm, the combination of a breech-bolt, a firing-pin in said breech-bolt, a detent mounted directly upon said breech-bolt for locking said firing-pin in inoperative position, means for automatically locking and unlocking said breech bolt, and means actuated by said locking means for actuating said detent.

2. In an automatic firearm, the combination of a breech-bolt, a firing-pin in said breech-bolt, a detent pivoted directly upon said breech bolt and having a cam surface adapted to engage said firing pin to retain it in inoperative position, means for automatically locking and unlocking said breech bolt, and means actuated by said locking means for actuating said detent.

3. In an automatic firearm, the combination of a breech-bolt, a firing-pin therein, a detent for said firing pin, locking means for said breech-bolt independent of the breech bolt, and means actuated by said locking means for actuating said detent.

4. In an automatic firearm, the combination of a breech-bolt, a firing pin therein, a detent for said firing-pin, locking means for said bolt, a sliding cam plate for actuating said locking means, and means actuated by said cam plate for actuating said detent.

5. In an automatic firearm, the combination of a breech bolt, a firing pin therein, a detent for said firing-pin, locking means for said breech-bolt, a sliding cam plate for automatically actuating said locking means, a connecting rod having a pin and slot engagement with said sliding cam-plate and actuating said detent to lock said firing-pin in inoperative position upon movement of said plate to actuate said locking means to unlock said breech-bolt, and actuating said detent to unlock said firing-pin upon movement of said plate to actuate said locking means to lock the breech-bolt.

6. In an automatic firearm, the combination of a breech-bolt, a firing-pin therein, a detent for said firing-pin, locking levers for said breech-bolt, a sliding cam-plate for automatically actuating said locking levers, and means actuated by said cam-plate for actuating said detent to lock and unlock said firing-pin in accordance with the unlocking and locking of said breech-bolt.

7. In an automatic firearm, the combination of a breech-bolt, a firing-pin therein, a

detent for said firing-pin, locking levers for
said breech-bolt, a recoil-actuated sliding
cam-plate for actuating said locking levers,
and means actuated by said cam-plate for
5 actuating said detent to lock and unlock said
firing-pin in accordance with the unlocking
and locking of said breech-bolt.

In witness whereof, I have hereunto signed
my name in the presence of two subscribing
witnesses.

PAUL MAUSER.
